GAS PURIFIER BOX CONSTRUCTION

George C. Pfaff, Baltimore, Md., assignor to Koppers Company, Inc., a corporation of Delaware

Application June 10, 1949, Serial No. 98,320

9 Claims. (CL 220—71)

1

My invention relates to an improved gas purifier box of the type adapted to contain a purifying substance through which manufactured gas is passed under pressure.

As usually constructed, gas purifier boxes or tanks are large closed structures in which there are removable trays on which is supported purifying material which may be a mixture of iron oxide and wood shavings. The effectiveness of the purifying material decreases with use and this material must be replaced at intervals. Accordingly, the purifier boxes are usually provided with covers which are removable so that the purifying material may be readily removed and replaced.

These boxes are relatively large, being on the order of thirty feet square and fifteen feet high, and the gas therein is at a substantial pressure, such as two to three pounds or more to the square inch. Because of the large area of each of the side walls, and the substantial pressure of the gas within a box, the total force exerted on a wall is considerable, and to enable the walls to withstand these forces braces have been provided between the upper edges of the walls on opposite sides of a box. These braces interfere with the removal of spent purifying material by means of mechanical devices, such as a clam shell bucket.

An object of this invention is to provide an improved gas purifier box which is arranged so that the top of the box is open and free of restrictions when the cover is removed.

A further object of the invention is to provide an improved gas purifier box which is arranged so that the braces which connect the upper parts of opposite side walls of the box together are incorporated in the removable cover so as to be removed when the cover is removed.

Another object of the invention is to provide an improved gas purifier box which incorporates removable braces connecting the upper parts of opposite side walls, and is arranged so that these braces are effective when the box is in service and are ineffective when the box is taken out of service.

A further object of the invention is to provide an improved gas purifier box having a surrounding upstanding side wall in the form of side walls surrounded at the top by a substantially flat sealing surface extending completely around the box, together with a removable cover clamped against this sealing surface to form a gas-tight joint, and having cross-braces located in fixed relation inside the cover and removable therewith at a level above the sealing surface and cooper-

2

ating with the upstanding side wall by means in the form of brackets secured to the side walls to prevent expansion of the side walls while the box is in service.

Another object of the invention is to provide an improved gas purifier box having side walls surrounded at the top by a reinforcing member of relatively large size and also provided at the top by a substantially flat sealing surface extending completely around the box together with a cover clamped against this sealing surface, and having detachable braces associated with the cover and cooperating with brackets secured to the reinforcing member to prevent expansion of the side walls while the box is in service.

A further object of the invention is to provide an improved purifier box which is arranged so that when the cover is in place on the side walls of the box, the tops of opposite side walls are connected together through braces incorporated in the cover.

Other objects of the invention and features of novelty will be apparent from the following description taken in connection with the accompanying drawings in which:

Fig. 1 is an elevational view of a box embodying my invention with portions broken away to show the interior of the box;

Fig. 2 is a top plan view of the box shown in Fig. 1 with a portion of the cover and of the upper part of the side walls broken away;

Fig. 3 is an enlarged fragmentary view illustrating one of the hold-down bolts employed to hold the cover in place;

Fig. 4 is an enlarged fragmentary top plan view of a tie rod bracket;

Fig. 5 is an enlarged sectional view taken substantially along the line V—V of Fig. 4;

Fig. 6 is a fragmentary view taken substantially along the line VI—VI of Fig. 7 and showing a modification which I may employ; and

Fig. 7 is a sectional view taken substantially along the line VII—VII of Fig. 6.

Similar reference numbers refer to similar parts in each of the several views.

The gas purifier box provided by this invention is similar in construction to the boxes heretofore employed and is a large rectangular box with a surrounding upstanding side wall of substantial height in the form of side walls which are formed of steel plate and have vertically extending braces at intervals, while a relatively large channel member extends around the upper edge of the side walls to reinforce them. The top edge of the side walls has a substantially flat sealing surface

formed thereon and extending completely around the box. A removable cover is detachably secured on the top of the box and is clamped against the sealing surface to form a gas-tight joint. The cover has associated therewith tie rods which extend across the inside of the cover and are adapted to be secured to brackets mounted on the reinforcing member at the top of the side walls. The tie rods extend between opposite side walls and prevent expansion of the side walls by gas under pressure within the box. When the cover is removed to permit replacement of the purifying material, the pressure within the box is reduced to atmosphere and the tie rods are not required to prevent expansion of the side walls. As the tie rods are mounted in the cover and are fixed thereto and removable with the cover, the top of the box is completely open and free of restrictions when the cover is removed. Hence, 20 mechanical equipment, such as a crane with a clam shell bucket, may be employed to remove the spent purifying material and to install new material. When the cover is replaced, the tie rods are also automatically replaced and are secured to the surrounding upstanding wall as by 25 brackets so that these tie rods are effective to prevent expansion of the side walls before pressure is built up within the box.

In a modification the braces within the cover are employed as part of the means for preventing expansion of the side walls. The cover has on its exterior projections which connect with the braces within the cover and are adapted to be detachably secured to brackets on the side walls so that opposite side walls are connected together through the bracing in the cover.

Referring to the drawings, the purifier box shown therein is fabricated from structural steel and is built upon a reinforced concrete foundation 10 on which there is mounted a steel floor plate 11. The floor plate 11 covers the interior of the box and extends slightly beyond the side walls 12 of the box. The side walls 12 are formed of steel plate, and each wall is provided at intervals with vertical stiffeners or braces in the form of I-beams 14. The lower ends of the I-beams 14 rest on supporting plates 13 and are secured to the floor plate 11 by suitable means, as by welding, so that the floor plate serves to connect together the I-beams associated with opposite side walls of the box. The lower edges of the side walls 12 are also secured to the floor plate 11 by suitable means, such as welding, to form a gas-tight joint.

The construction of the upper edge of each of the side walls 12 is best shown in Figs. 3 and 5 of the drawings. As therein illustrated, the upper end of each I-beam 14 has an inner corner removed, while a horizontally extending channel 15 rests on the lower part of the recess in each I-beam. The channel 15 has its flanges projecting outwardly and is mounted in such manner that the inner face of the web of the channel 15 is substantially in the same plane as the inner face of each of the I-beams 14 so that the channel 15 and I-beams 14 present a smooth surface for the plates forming a side wall 12 to press against.

The channel 15 is about twice as wide as the recess or cut out section in the I-beams 14 so the channel 15 extends above the upper ends of the I-beams 14.

A relatively wide channel 16 is mounted on the tops of the I-beams 14 with the inner face of the channel 16 engaging the web of the channel 15 substantially in the region in which the opposite

face of the web of the channel 15 is engaged by the upper edge of the plates forming a side wall 12. The flanges on the channel 16 are on the lower face of the channel. The channel 16 is secured to the upper ends of the beams 14 by suitable means, as by welding, while the channels 15 and 16 may be welded together and the channel 15 may be welded to the I-beams 14. In addition, the plates forming a side wall 12 are welded to the channel 15 to form a gas-tight joint.

The channels 15 and 16 extend across an entire side of the purifier box and at each end are secured to counterpart channels associated with an adjoining wall. Accordingly, the upper edge of the side walls of the purifier box is completely surrounded by channels which stiffen the walls and prevent their deformation. The channel 16, because of its great width and the horizontal disposition of its web, is extremely effective to prevent deformation of a wall.

Furthermore, the upper face of the channels 15 provides a substantially flat, rigid sealing surface extending completely around the box and against which the removable cover is adapted to be clamped.

The purifier box is provided with a removable cover which is built up from structural steel and is indicated generally by the reference character 20. The upper surface of the cover is convex between one pair of side walls and is substantially straight between the other pair of side walls.

Two sides of the cover are formed of channels 21 which have their flanges turned inwardly, while the other two sides of the cover are formed of built-up members 22, each of which has on its lower edge an inwardly extending flange similar to the lower flange on one of the channels 21. Each of the members 22 also has on its upper edge an inwardly extending flange similar to the upper flange on one of the channels 21. In addition, each of the members 22 has a plurality of vertically disposed reinforcing members 23 extending between the upper and lower flanges on the member.

The channels 21 and the members 22 are secured together at the corners of the cover and are arranged so that the faces of the flanges on the lower edges of the channels 21 and of the members 22 are in substantially the same plane throughout the circumference of the cover. The flanges on the bottoms of the channels 21 and of the members 22 provide a relatively rigid, substantially flat sealing surface which extends completely around the cover and is adapted to confront the sealing surface surrounding the top of the side walls of the box.

The members 22 on opposite sides of the cover are connected by a plurality of parallel cross-braces 25, each of which is of substantially the full vertical extent of the cover in the area in which the brace is situated. Each of the braces 25 is secured at each end to one of the members 22 by suitable means, as by welding.

The channels 21 on opposite sides of the cover are connected by a plurality of parallel cross-braces 26, each of which is in the form of a plurality of sections. The sections of each brace 26 extend between one of the channels 21 and one of the braces 25, or between different braces 25, and are connected together through the braces 25 so as to form effective structural ties connecting the channels 21 together. The lower faces of the braces 26 are substantially straight, but the upper surfaces of the braces 26 are curved so that the upper faces of the braces 26 are sub-

stantially in the same plane as the upper faces of the side members 22.

The top of the cover is covered by steel plate 27 which is secured to the channels 21, the members 22, and the braces 25 and 26 to form a gas-tight structure.

As shown in Fig. 1 of the drawings the cover is provided with a plurality of projections 30 which serve as hooks or points of attachment by means of which the cover may be lifted by a crane or hoist. The projections 30 are secured on the top of the cover at points at which the braces 25 and 26 intersect.

The internal braces 25 and 26 cooperate with the side members 21 and 22 to form a rigid structure which can withstand the forces exerted thereon by the gas under pressure within the box, and by the weight of the cover when the cover is lifted off the side walls. The internal braces 25 and 26 connect opposite sides of the cover together and prevent expansion of the side members 21 and 22 by gas under pressure within the box, while the braces 25 and 26 prevent the plates 27 from being deformed by the gas under pressure within the box.

This purifier box is provided with means to detachably secure the cover 20 on the box. This means comprises a plurality of hold-down bolts which are located a short distance apart throughout the periphery of the box. The construction of one of the hold-down bolts and the associated apparatus is illustrated in Fig. 3 of the drawings.

As shown in Fig. 3 of the drawings a pair of spaced vertical plates 31 are secured to the upper face of the channel 16 and to the outer face of the channel 15. A hold-down bolt 32 having an eye at its lower end is mounted between the plates 31, while a pin 33 extends through aligned openings in the plates 31 and also through the eye of the bolt 32. In this manner each hold-down bolt 32 is pivotally secured to a side wall of the box so that the upper end of the bolt may be moved towards and away from the cover 20.

The cover has secured on its side faces brackets 35 which project from the faces of the cover and are adapted to receive the upper ends of the eye bolts 32. Each of the brackets 35 comprises a pair of spaced parallel plates which are secured on a side face of the cover 20 and have substantially horizontal upper edges. The plates forming each bracket 35 are spaced apart far enough to permit one of the bolts 32 to move between them. A small plate 37, notched at its outer edge to receive a bolt 32, is secured on the upper edges of the vertical plates of a bracket 35. The upper or free end of each bolt 32 is threaded and is adapted to receive a cap nut 38, the lower side of which is provided with a flange which is adapted to engage the plate 37 on a bracket 35.

The brackets 35 are secured on the cover 20 at such points that when the cover is in position on the side walls of the box a bracket 35 is located above each hold-down bolt 32. As is clear from Figs. 1 and 2 of the drawings, there is a hold-down bolt 32 and a bracket 35 at each corner of the purifier box, while there are a large number of hold-down bolts on each side wall.

As is best shown in Figs. 3 and 5 of the drawings a strip of packing 39 is clamped between the cover and the side walls of the box. The packing 39 may be formed of any suitable material, such as asbestos reinforced with wire,

and extends completely around the box to form a gas-tight joint between the cover and the side walls. The packing 39 is secured to the cover 20 by suitable rivets or bolts, the lower ends of which are countersunk in the packing.

When the box is in service, the nuts 38 on the hold-down bolts 32 are tightened down to clamp the packing strip 39 between the cover and the side walls and thus prevent escape of gas under pressure through the joint between the cover and the side walls.

The interior of the box is provided with removable trays 40 on which is supported purifying material 41 which may be a mixture of iron oxide and wood shavings. The box is also provided with inlet and outlet connections through which gas is supplied to and discharged from the box in such manner that the gas must pass through a layer or layers of purifying material in passing through the box. The trays 40, as well as the inlet and outlet connections, may be arranged in any suitable well known manner, and as these details are not necessary to understanding of this invention, they are being omitted in order to simplify this disclosure.

The cover 20 has associated therewith tie rods 42 which cooperate with brackets 43 on the side walls of the box to prevent expansion of the walls. Referring to Fig. 2 of the drawings, it will be seen that there are four tie rods 42, two rods extending in each direction across the box and being located so that the distance between each pair of rods, and between the rods and the ends of a wall is substantially uniform.

Each of the rods 42 is of substantial size, such as two inches in diameter, and is located a short distance above the lower face of the cover. Each of the rods 42 extends through aligned openings provided in the braces 25 and 26, and is of such length that the ends of the rod project from the sides of the cover a short distance, as shown in Fig. 5. The joints present where the rods 42 pass through the side walls of the cover are sealed by welding the rods to the cover.

Each of the side walls is provided with brackets indicated generally by the reference character 43 and adapted to receive the projecting ends of the tie rods 42. Referring to Figs. 4 and 5, it will be seen that the channel 16 has an opening therethrough and that a member 46 extends through this opening. The lower end of the member 46 engages the inner face of a channel 47 which extends between adjacent I-beams 14 and is secured to these I-beams as well as to the lower face of the channel 16.

The portion of the member 46 which extends above the channel 16 is bifurcated and has a slot therein of such width as to freely receive the end of a rod 42. A pair of spaced angular reinforcing members 48 are secured to the upper face of the channel 16 and extend between the member 46 and the channel 15, the members 48 being welded to the member 46 and to the channels 15 and 16. As is clearly shown in Fig. 5 the members 48 are cut to fit the space between the channel 16 and the upper flange of the channel 15, while the members 48 extend away from the channel 15 so as not to interfere with the cover 20. As is clearly shown in Fig. 4, the braces 48 are spaced apart far enough that the upper ends of these members are not engaged by the tie rod 42.

A single, substantially triangular reinforcing member 50 extends between the outer face of

the member 46 and the upper face of the channel 16. As shown in Fig. 5, the member 50 is of such vertical height that it does not extend above the bottom of the slot in the member 46 and therefore does not interfere with the tie rod 42, nor with the nut on the end of the tie rod. As shown in Fig. 4 the reinforcing member 50 is located centrally of the member 46 and is substantially in alignment with the slot or recess in the member 46. The reinforcing member 50 is secured to the channel 16 and to the member 46 by welding.

The free end of each of the tie rods 42 is threaded and has mounted thereon a nut 51 which engages the face of the member 46.

Each end of each tie rod 42 has a nut 51 thereon and when the nuts on opposite ends of a tie rod are tightened, the opposite side walls are drawn together and are thereafter prevented from expanding by the tie rods 42 which are under tension. The force exerted on the side walls by the gas under pressure within the purifier box causes the tension on the tie rods 42 to be increased, while force is exerted on the brackets 43 tending to move the upper end of each bracket inwardly, and to move the lower end of each bracket outwardly. However, the braces 48 and 50 prevent inward movement of the upper end of each bracket 43, while the channels 17, which are secured to the I-beams 14, prevent outward movement of the lower end of each bracket. Hence, the brackets 43 are extremely rigid and effectively transmit force between the side walls and the tie rods. In addition, it will be seen that the brackets 43 are mounted on and are secured to the channels 16 which reinforce the upper edge of the side walls of the box.

The gas within the box can only be under pressure while the cover is in place, and as long as the cover is in place, the tie rods 42 are effective to connect the upper part of opposite side walls together and prevent expansion of the walls by the gas under pressure within the box.

When the purifying material 41 is to be replaced, the box is taken out of service, and the pressure of the gas within the box is reduced to atmospheric pressure with the result that force is no longer exerted on the side walls of the box tending to expand them. The nuts 38 on the hold-down bolts 32 are now loosened, each nut being loosened enough to permit the associated bolt to be swung free of the bracket 35. The nuts 51 on the tie rods 42 are also loosened, and the cover is lifted from the top of the box by a crane or hoist, not shown, and is removed from above the box. When the cover is lifted off the side walls of the box, the tie rods 42 are lifted out of the slots or recesses in the brackets 43. The top of the box is now completely open and unobstructed so that mechanical equipment may be employed to remove and replace the purifying material. In addition, the removable trays 40 may be removed and replaced with a minimum of difficulty.

After the new purifying material has been installed, the cover 20 is brought to a position above the side walls of the box and is then lowered so that the ends of the tie rods 42 are received in the slots or recesses in the brackets 43. At this time the sealing surface surrounding the lower face of the cover 20 rests on the gasket 39, while the gasket 39 rests on the upper face of the channels 15.

The hold-down bolts 32 are now swung upwardly to their vertical positions, and the nuts

38 are tightened to draw the cover 20 down and clamp the gasket 39 between the cover and the side walls. In addition, the nuts 51 on the ends of the tie rods 42 are tightened to build up an initial tension on the tie rods and prevent subsequent expansion of the side walls.

The box is now ready to be placed in service and when the pressure of the gas within the box is built up, force is exerted on the side walls tending to expand them, but their expansion is prevented by the tie bolts 42.

It will be seen that expansion of the upper edge portion of the side walls of the box by the gas under pressure within the box is prevented by tie rods extending between opposite side walls. These tie rods are incorporated in the cover and are removed when the cover is removed. Hence, when the cover is removed, the tie rods are removed and the upper face of the box is unobstructed. When the cover is removed, the gas within the box is no longer under pressure and the tie rods are not required to prevent expansion of the side walls. The cover must be replaced before the pressure within the box can be built up, and as the tie rods are replaced when the cover is replaced, the tie rods are effective when they are needed.

In the species heretofore described special tie rods are incorporated in the cover and serve to connect the upper edges of opposite side walls together. It is not necessary to provide special tie rods for this purpose as the internal bracing in the cover may be employed for this purpose, and Figs. 6 and 7 illustrate this modification.

Referring to Figs. 6 and 7 of the drawings it will be seen that the cover 20a has secured to the exterior thereof a projection 60 which is in the form of a vertically disposed plate. The member 60 is mounted on the side of the cover in alignment with one of the internal braces, such as a brace 26a, extending across the inside of the cover. Each of the members 60 is secured to the exterior of the cover in such manner as to be connected directly to the associated brace within the cover. As shown in the drawings the interior brace 26a has angles 62 at the end which engage the inner face of the channel 21. The projection 60 is provided with similar angles 63 which engage the outer face of the channel 21. The angles 62 and 63 are secured together by rivets 64 which extend through the channel 21. The free end of each projection 60 is adapted to extend through the slot or recess in the top of a bracket 43a which is similar to the bracket illustrated and described in connection with the tie rods. The free end of each projection 60 has therein a rectangular slot or opening 65 which is located so that most, but not all, of this slot is beyond the outer face of the bracket 43a. The slot 65 is adapted to receive a wedge 67 while the outer face of the bracket 43a has therein a groove 68, which is somewhat wider than the slot 65 or the wedge 67.

A wedge 67 is inserted in a slot 65 and is driven tight by suitable means, such as a sledge hammer, with the result that the outer face of the wedge exerts force on the outer edge of the slot 65 in the projection 60 to exert tension on the projection 60 and thus exert tension on the associated brace within the cover.

Each side of the cover 20a is provided with a plurality of projections 60 which are spaced apart throughout the length of that side of the cover so that opposite side walls of the box are

connected together through the cover at a plurality of places.

When the cover is to be removed, the wedges 67 are removed and after the hold-down bolts have been released, the cover may be lifted off. When the cover is to be replaced, the cover is placed on the box so that the projections 60 enter the slots in the tops of the brackets 43a. After the hold-down bolts have been tightened, the wedges 67 are inserted and driven tight. Thereafter, the side walls are prevented from expanding because the side walls are connected together through the braces in the cover.

This modification, like that heretofore described, provides means associated with the cover for preventing expansion of the upper parts of the side walls while the box is in service, while this means is arranged so that when the cover is removed, the top of the box is completely unobstructed.

Furthermore, it will be seen that both modifications of the box provided by this invention are arranged so that the means for connecting opposite side walls together when the cover is in place are completely independent of the sealing surfaces on the cover and side walls. Hence, the sealing surfaces remain flat surfaces and provide an effective seal between the cover and the side walls.

Although I have herein illustrated two forms of improved gas purifier box embodying my invention, it should be understood that the invention is not limited to these details of construction and that numerous modifications and changes may be made without departing from the spirit and scope of the following claims.

Having thus described my invention, what I claim is:

1. In a gas purifier box of the type described having pairs of substantially parallel side walls and having a cover with means for detachably securing the cover on the top of said side walls with a tight seal, the combination of tie rods for preventing outward movement of the upper edges of said side walls by gas under pressure within the box while leaving the upper face of the box completely unobstructed when the cover is removed, and brackets secured on said side walls, said tie rods extending across said cover on the inside thereof and being fixed thereto for removal therewith, said tie rods having their ends projecting from said cover in position to fit into said brackets, at least one tie rod extending between each opposite pair of side walls, and means for detachably securing the ends of said tie rods to said brackets when said cover is in position on said side walls.

2. In a purifier box of the type having substantially parallel side walls and having a cover with means for detachably securing the cover on the top of said side walls, the combination with the foregoing apparatus of means for preventing outward movement of the upper edges of said side walls by gas under pressure within the box while leaving the upper face of the box completely unobstructed when the cover is removed, said means comprising tie rods extending across said cover and having their ends projecting from said cover, at least one tie rod extending between each opposite pair of side walls, and means for detachably connecting the ends of said tie rods with said side walls, said last named means comprising brackets mounted on said side walls and having therein recesses

60 70 75

open on their upper faces, said recesses being adapted to receive the ends of said tie rods.

3. In apparatus of the class described, a box having substantially parallel side walls, a cover detachably secured on said side walls, said cover and said side walls being surrounded by sealing surfaces which confront each other when the cover is in position on said side walls, tie rods extending across said cover and having their ends projecting through the sides of said cover above the sealing surface on said cover, at least one tie rod extending between each opposite pair of side walls, and means for detachably securing the ends of said tie rods to said side walls.

4. In apparatus of the class described, a box having substantially parallel side walls, a cover with means for detachably securing it on said side walls, said cover and said side walls being surrounded by sealing surfaces which confront each other when the cover is in position on said side walls, said cover including cross-braces which extend between opposite pairs of sides of said cover, said cover having on each side thereof at least one projecting member which extends outwardly from said cover, the projecting members on opposite sides of said cover being connected together through one of said cross-braces, and means for detachably connecting said projecting members to said side walls.

5. In apparatus of the class described, a box having substantially parallel side walls, a cover having means for detachably securing it on top of said side walls, said cover and said side walls being surrounded by sealing surfaces which confront each other when the cover is in position on said side walls, said cover including cross-braces which extend between opposite pairs of sides of said cover, said cover having on each side thereof an external projection located substantially in alignment with one of said cross-braces, the projections associated with opposite side walls being substantially in alignment with the same cross-brace and being connected together through such cross-brace, and means for detachably securing said projections to said side walls.

6. In apparatus of the class described, a box having substantially parallel side walls, a cover detachably secured on said side walls, said cover and said side walls being surrounded by sealing surfaces which confront each other when the cover is in position on said side walls, clamping means for detachably connecting the cover in sealing position on the side walls, each of said side walls having secured thereon adjacent its upper edge a bracket having a recess opening on its upper face, and means extending across said cover with end members extending through the recesses in said brackets when the cover is in position on said side walls for preventing outward movement of said side walls by fluid under pressure within said box.

7. In apparatus of the class described, a box having substantially parallel side walls, a cover detachably secured on said side walls, said cover and said side walls being surrounded by sealing surfaces which confront each other when the cover is in position on said side walls, clamping means for detachably sealing said cover on top of said side walls, each of said side walls having secured thereon adjacent its upper edge a bracket which extends above the sealing surface on said side wall and has in the portion above said sealing surface a recess opening on the upper face of said bracket, and means carried by said cover and extending through the recesses in said brack-

ets when the cover is in position on said side walls for preventing outward movement of said side walls by fluid under pressure within said box.

8. In apparatus of the class described, a box having substantially parallel side walls, a cover detachably secured on said side walls, said cover and said side walls being surrounded by sealing surfaces which confront each other when the cover is in position on said side walls, clamping means for detachably sealing said cover on the top of said side walls, each of said side walls having secured on the outer face thereof a bracket which extends above the sealing surface on said side wall and has in the portion above said sealing surface a recess opening on the upper face of said bracket, projections on said cover which extend through the recesses in said brackets when the cover is in position on said side walls, and means within the cover and connecting together the projections on opposite sides of said cover.

9. In a gas purifier box of the type described, having a surrounding upstanding side wall and having a removable cover with means for detachably securing the cover on the top of said side wall with a tight seal, and cross braces for preventing outward expansion movement of the upper edges of said surrounding side wall by gas under pressure within the box, the improvement characterized by said cross braces extending across the inside of the cover and being fixed

thereto for removal with the cover, and brackets fixed to said surrounding side wall, said cross braces having ends projecting from said cover in position to fit into said brackets fixed to said surrounding side wall, and means for detachably securing the projecting ends of said cross braces to said brackets when said cover is in position on top of said box side wall.

GEORGE C. PFAFF.
